UNITED STATES PATENT OFFICE.

THOMAS L. HARRISON, OF PHILADELPHIA, PENNSYLVANIA.

COLLAPSIBLE-TUBE-CLOSING MACHINE.

1,425,961.

Specification of Letters Patent. Patented Aug. 15, 1922.

Application filed August 1, 1921. Serial No. 488,837.

To all whom it may concern:

Be it known that I, THOMAS L. HARRISON, a citizen of the United States, and a resident of Philadelphia, in the county of Philadelphia and State of Pennsylvania, have invented an Improvement in Collapsible-Tube-Closing Machines, of which the following is a specification.

My invention relates to machines for closing the rear initially open ends of collapsible tubes, such as those in which tooth paste and other paste of plastic products are sold.

One of the objects of my invention is to provide a machine which is capable of more rapid operation than machines of similar character heretofore, as far as I am aware, constructed, so that a greater number of tubes may be closed in any given period of time than previously has been practical.

20 A further object of the invention is to simplify the construction of the machine to thereby enable its manufacture at a substantial reduction in cost.

To these and other ends, the invention comprehends the construction as herein-after described and illustrated in the drawings in which I have illustrated one form of construction embodying said invention. It will be understood, however, that changes 30 in the details of construction may be made within the scope of the claims without departing from the invention.

In the drawings:

Fig. 1 is a top plan view of a machine embodying my invention;

Fig. 2 is a view, partly in vertical section and partly in front elevation;

Fig. 3 is a view in side elevation of the machine, looking toward the left in Figs. 1 and 2; and

Figs. 4, 5, 6, 7 and 8 are views indicating different steps in the operation of closing the end of a collapsible tube by means of the said machine.

45 Referring to the drawings: 1 designates the base portion of a machine having a post or standard 2 thereon upon which the revolving work carrying table 3 is mounted. Adjacent the periphery of this table, openings 4 are provided at intervals which openings are provided with shoulders 5 adjacent their lower ends. The top ends of the collapsible tubes, that is to say, the ends with the removable caps thereon are inserted within these holes or openings and are supported

therein, as indicated in Fig. 2 of the drawings. The tubes, the rear ends of which are to be closed, are placed in position within these openings and are conveyed by the revoluble carrier 3 into position between the 60 clamping jaws of the machine which will be hereinafter referred to and described.

The revoluble carrier 3 is provided upon its lower side with a beveled gear 8 with which the beveled pinion 9 is in engagement, as shown in Fig. 2 of the drawings. The said beveled pinion 9 is supported upon the inner end of a shaft 10, the latter being supported upon bearings, one of which is shown at 11. The outer end of the shaft 10 is provided with a ratchet wheel 12 with the teeth of which a pawl 13 is adapted to successively engage. The said pawl is carried by a projection 14 near the lower end portion of a link 15. The lower end portion of the said link is provided with a slot 16 through which a headed pin 17 projects, the said link being adapted to slide back and forth upon the said pin 17. The upper end of the link is connected to a pin 20 which projects outwardly from the outer side of the gear wheel 21 which is in engagement with a pinion gear 22 upon a shaft 23 upon one end of which a band wheel 24 is secured. The said band wheel 24 and consequently 75 shaft 23 is driven by means of a belt 25 from a source of power (not shown). The gear 21 is supported upon a stud 28 projecting outwardly from a plate-like portion 29 which extends upwardly from the base portion 1 and constitutes what may be regarded as a part of the frame supporting structure 80 of the machine.

Upon the rotation of the shaft 23, the gear 21 is driven by the gear 22 upon the said 95 shaft 23. The rotation of the gear 21 causes reciprocating movement of the link 15. Such reciprocating movement causes the pawl 13 to successively engage the teeth upon the ratchet 12. As the pawl 13 is 100 moved upwardly by the link 15 it travels over the outer ends of the said teeth, but when the said link starts its downward movement, the pawl engages one of the teeth succeeding that with which it was formerly 105 engaged and causes rotation of the said ratchet wheel and of the shaft 10 through a single step, the distance corresponding to the distance between the ratchet teeth. Such movement of the ratchet wheel of the 110

shaft 10 causes a step by step movement of the revoluble carrier 3. The distance through which the latter may be caused to move at each step may be controlled by the 5 ratio between the number of teeth upon the beveled pinion gear 9 and the beveled gear 8. The shaft 23 is supported in bearings 30 upon the upwardly extending plate-like portion 29.

10 For the purpose of closing the rear initially open ends of the collapsible tubes which are carried upon the revoluble carrier 3, I have provided co-operating clamping jaws 31 and 32, the first of which is supported between laterally and forwardly extending 15 projections 33, two of which are situated above and two below the same. Retaining plates 34 are secured to the outer ends of these projections for retaining the jaw 31 20 in position between the upper and lower projections.

The jaw 32 is supported within a guide or housing 41 formed upon a bracket 42 projecting forwardly from the plate-like portion 29 and is provided upon its opposite sides with grooves 42' into which extend 25 projections 43 from the opposite sides of the said housing. The jaw 32 is provided with a recess 44 the top side of which is open.

30 A slide plate 45 extends across the upper or top side of the recess 44 and its opposite edges are supported upon shoulders upon the top side of the jaw 32 at the opposite sides of the said recess, as is clearly indicated in Fig. 3 of the drawings. The said slide plate 45 is retained in position upon the said shoulders by means of holding or locking plates 48 secured to the top side of the said jaw upon opposite sides of the recess 44. The inner edges of these plates 48 35 overlie the outer edges of the slide plate 45. The slide plate 45 is provided with a projection 50 which extends into the recess 44. Interposed between said projection and the inner end of the recess 44 is a coiled spring 40 51 which is under tension and tends to hold the slide plate 45 in its outermost position with the opposite side of the projection 50 in contact with an adjustable abutment 45 screw 52 having adjustable connection with the outer end portion of the jaw 32. The said slide plate 45 is also provided with an upwardly extending projection 53 which is pivotally connected at 54 with the lower side 50 of a turning lever 55. The connection at 54 is situated at a point relatively near the outer end of the turning lever 55. For the purpose of effecting reciprocating movements of the jaws 31 and 32, I have pro- 55 vided the levers 60 and 61 both of which are pivoted at their upper ends, as indicated at 62, to the upper end portion of the plate-like member 29. Intermediate their ends, the levers 60 and 61 are each provided with 60 inwardly extending projections having rolls

thereon, as indicated at 63, which project into and engage the cam slots 64 and 65 upon the cam members 66 and 67 which are secured upon the shaft 23. The lower end of the lever 60 is pivotally connected directly with the clamping jaw 31, as indicated at 70. The lower end of the lever 61 is connected to the turning lever or arm 55 at a point above the pivot 54, as is indicated at 75 71. It will be apparent that as the shaft 23, together with the cam members 66 and 67, are rotated, the levers 60 and 61 are oscillated to cause rectilinear reciprocating movement of the clamping jaws 31 and 32.

In Fig. 4 of the drawings, the clamping 80 jaws are shown in separated position with the unclosed end of a collapsible tube in position between the inner opposing ends thereof. In Figs. 2 and 5, the jaws are shown in position with the upper rear end 85 portion of the tube clamped between the same and flattened. It will be noted that the cam groove 64 is so shaped that as the cam member 66 continues its rotation in the direction indicated by the arrow thereon 90 from the position shown in Fig. 2, the jaw 31 will be retained in stationary position, but the cam groove 65 for operating the jaw 32 is so shaped that corresponding rotation of the cam member 67 causes continued inward movement of the lower end portion 95 of the lever 61 which causes inward movement of the tube turning arm 55 and with it the slide plate 45 in opposition to the tension of the spring 51. At such time, further inward movement of the jaw 32 is prevented by reason of the fact that the inner end of the adjustable abutment screw 73, which has screw threaded adjustable connection with a projection 74 which extends 100 downwardly from the outer end of the said jaw 32, contacts with the outer side or edge of the bracket 42.

The further inward movement of the slide 105 plate 45 and of the turning lever 55 independently of the jaw 32 causes the end of the downwardly extending portion 75 at the inner end of the lever 55 to contact with the flattened portion 76 of the collapsible tube which projects above the top sides of the 110 jaws 31 and 32 to bend the same over upon the jaw 31, as shown in Fig. 6. Immediately following this occurrence, the cam groove 64 in the cam member 66 causes outward movement of the jaw 31 into the position indicated in Fig. 7. By means of the pressure of the spring 51 against the slide plate 45 and by reason of the pivotal connection between the latter and the lever 55, the latter is turned about its pivot so that the inner end thereof is lowered from the position shown in Fig. 6 to that shown in Fig. 7, to bend the flattened end portion 76 of the tube downwardly, as indicated in said Fig. 7, with a surface thereof in contact 115 120 125 130

- with the inclined surface 78 upon the under-side of the downwardly projecting portion 75 of the turning lever 55. Immediately following this occurrence, the cam groove 65 in the cam member 67 causes outward movement of the lever 61, the first effect of which is to cause the slide plate 45 to move outwardly so as to bring the projection 55 into contact with the adjustable screw 52.
- 10 The cam is so shaped, however, as not to cause at this time further outward movement of the slide plate 45 and the jaw 32 upon which said plate is carried, with the result that the clamping jaw 32 remains in the position in which it is shown in Fig. 2. The previous outward movement, however, of the lever 61 has caused the turning lever 55 to return to the position in which it is shown in Figs. 2, 4 and 5. Immediately 15 upon the return of the lever 55 from the position shown in Fig. 7 to that shown in Figs. 2, 4, 5 and 8, the cam which controls the lever 60 causes inward movement thereof to press the clamping jaw 31 against the downwardly turned flattened end portion 76 of the tube to compress the same, as shown in Fig. 8 of the drawings. From the positions shown in Fig. 8, the jaws are moved to the positions shown in Fig. 4 by the action 20 of the cams which control the oscillatory movements of the levers 60 and 61.
- To prevent the turning lever 55 from turning too great an extent toward the right about its pivot at 54, the outwardly extending 25 projections 80 are provided which normally, as shown in Figs. 2 and 3, are situated closely adjacent to the upper sides of the retaining plates 48 but not quite in contact therewith.
- 30 It will be seen that I have provided a machine of the character and for the purpose stated which comprises a minimum number of parts and the construction of which is extremely simple. By reason of the relatively 35 small number of parts employed in its construction and by reason of the relationship between the said parts, the said machine is capable of operating efficiently at unusual speed.
- 40 Having thus described my invention, what I claim and desire to secure by Letters Patent is:
1. In a collapsible tube closing machine, the combination of reciprocating jaws, means for causing reciprocation of said jaws into and out of clamping relation with respect to each other, a slide secured upon one of said jaws, a yielding means intermediate said slide and said jaw, and a member pivotally connected to said slide for turning the flattened end of a tube first laterally and then downwardly, the said member having connection directly with the means for actuating the said slide and jaw.
  - 65 2. In a collapsible tube closing machine,
- the combination of rigid rectilinearly movable clamping jaws, oscillatable lever having immediate connection with one of said jaws for causing reciprocation thereof, a pivoted member having connection with the other of said jaws, and an oscillatable lever having connection with said pivoted member and acting therethrough for causing reciprocation of said other jaw.
3. In a collapsible tube closing machine, 75 the combination of members adapted to clamp the rear initially open end of a collapsible tube to flatten the same, means for causing reciprocation of said members, one of said members being provided with a lever having pivotal connection therewith at a point adjacent the outer end of said lever, said lever being adapted to be moved longitudinally with respect to the said jaw, means having connection with said pivoted 80 lever for effecting reciprocation thereof and also of the jaw to which it is connected, and means for effecting pivotal movement of the said lever.
4. In a collapsible tube closing machine, 90 the combination of clamping jaws, oscillating means having connection with one of said jaws to cause reciprocation thereof, a pivoted lever, a yielding connection between said pivoted lever and the other of said jaws, 95 and oscillating means having connection with the said pivoted lever for causing reciprocation thereof and of the said jaw to which it is connected.
5. In a collapsible tube closing machine, 100 the combination of reciprocating jaws which are adapted to clamp the initially open rear end of a collapsible tube to flatten the same, means having connection with one of said jaws for causing reciprocation thereof, a 105 slide member secured upon the other of said jaws, yielding means tending to hold the member in its outermost position, a lever having pivotal connection with the said slide member the inner end of which is adapted 110 to contact with the outer flattened end portion of the said tube to turn the same laterally and downwardly, and means having connection with said lever for actuating the same together with the said jaw upon which the said lever is mounted.
6. In a collapsible tube closing machine, 115 the combination of jaws which are adapted to cooperate to clamp the initially opened end of a collapsible tube to flatten the same, a cam actuated lever having connection with one of said jaws for causing reciprocating movement thereof, a slide member mounted upon the other of said jaws, a spring interposed between the said slide and the said 120 jaw which tends to hold the said slide in its outermost position with respect to said jaw, a lever having pivotal connection with the upper side of said slide, the inner end 125 of said lever terminating in a downwardly 130

and inwardly extending portion which is adapted to contact with a portion of the said flattened portion of tube to turn the same laterally and downwardly, and an oscillating lever having connection with the said last mentioned lever at a point about its pivot for actuating the same together with the jaw upon which it is mounted.

7. In a collapsible tube closing machine, 10 the combination of reciprocating jaws which are adapted to clamp the initially open end of a collapsible tube to flatten the same, means for causing positive reciprocating movements of one of said jaws, a slide member upon the other of said jaws, a tube turning member pivotally connected with the said slide member, an oscillating member having connection with said tube turning member at a point above its connection with 15 said slide member, means for limiting the inward movement of said second named jaw, and means for thereafter causing further inward movement of the said slide member and the lever carried thereby.

25 8. In a collapsible tube closing machine, the combination of reciprocating clamping jaws, means for moving the said jaws into clamping position and holding the same in such position for an interval of time with 30 the flattened end of a tube held between the same, means adapted to be moved across the space between said jaws during such interval to bend the projecting end of said flattened portion of tube laterally against the 35 top surface of the end portion of one of said jaws, means for thereafter moving said last mentioned jaw outwardly away from the other jaw which remains stationary and the said second named means then operating 40 automatically to turn the previously turned flattened end portion of the tube downward and being thereafter returned to its original position, means for returning said outwardly moved jaw to compress the 45 said downwardly turned end portion of the tube against an adjacent portion of said tube, and means for thereafter moving both said jaws away from each other.

9. In a collapsible tube closing machine, 50 the combination of clamping jaws, oscillating levers for causing reciprocating movements of said jaws toward and from each other, a spring pressed slide member mounted on one of said jaws, said slide member 55 being movable independently of said jaw, a lever pivotally mounted on said slide member and having pivotal connection with the oscillating lever for causing reciprocating movements of the jaws on which said slide 60 is mounted, said pivotally mounted lever ex-

tending longitudinally of the said last mentioned jaw and terminating in an inwardly and downwardly extending portion at its inner end, and means for causing and permitting inward movements of said slide 65 member and said pivotal lever independently of the said jaw on which they are mounted and also for causing downward pivotal movement of the inner end of said lever.

70 10. In a collapsible tube closing machine, clamping jaws, a carrier for the tubes to be closed, means for causing step by step rotary movement of said carrier to convey said tubes successively between said jaws, 75 means having connection with one of said jaws for causing reciprocation of the same, a slide member upon the other jaw, a yielding member interposed between said jaw and slide member to permit relative movement between the two, a tube turning lever pivotally mounted on said slide member, and means having connection with said tube turning lever for effecting reciprocation of the said lever and the said slide with and 80 independently of the said other jaw.

85 11. In a collapsible tube closing machine, the combination of reciprocating jaws which are adapted to clamp the initial open bottom end of a collapsible tube to flatten the same, 90 means having connection with one of said jaws for causing reciprocation thereof, a slide member slidably secured upon the other of said jaws, a spring interposed between said slide member and its supporting jaw 95 which tends to hold the said slide member in an outward position, a lever having pivotal connection with the upper side of the said slide member, the inner end of which lever is adapted to contact with the flattened bottom end of said tube for turning the same, and the opposite outer end of which is adapted to contact with the said slide member to limit pivotal movement of said lever in one direction, and oscillating means 100 having connection with the said lever at a point above its pivotal connection to said slide member, the said oscillating means operating to cause reciprocating movements of the said slide member and its supporting 105 jaw, and the said spring operating after the said slide member has been moved to its innermost position and after withdrawal of the first mentioned jaw to cause quick descending movement of the inner end of the 110 said lever.

115 In testimony that I claim the foregoing as my invention, I have hereunto subscribed my name this 23rd day of July, 1921.

THOMAS L. HARRISON.
